UNITED STATES PATENT OFFICE.

JEAN FRANCIS WEBB, JR., OF NEW YORK, N. Y., ASSIGNOR TO THE INTERNATIONAL SIGNAL CO., A CORPORATION OF ARIZONA.

TRAIN-STOPPING MECHANISM.

Application filed December 30, 1922. Serial No. 609,864.

To all whom it may concern:

Be it known that I, JEAN FRANCIS WEBB, Jr., a citizen of the United States, residing at New York, in the county of New York and State of New York, have invented certain new and useful Improvements in Train-Stopping Mechanism, of which the following is a specification.

My invention relates to certain new and useful improvements in automatic train stopping systems of the mechanically operated electrically controlled type illustrated for example in my Letters Patent No. 1,433,582 issued October 31, 1922 and 15 1,170,789 issued February 8, 1916.

The present invention especially has for its object to provide certain improvements and refinements in the valve operating mechanism of the apparatus, particularly 20 in respect to the operating plunger, the holding latch for the rockable valve operating cam or shaft. There are other minor refinements and improvements in the design, construction and arrangement of 25 the parts which will become apparent hereafter and which are also included in the present invention.

The invention also resides in those novel features of construction, combination and 30 arrangement of parts, all of which will be first fully described and then be specifically pointed out in the appended claims, reference being had to the accompanying drawings, in which:

35 Figure 1 is a diagrammatic view of the air line connection in which the present invention is located.

Figure 2 is a wiring diagram of an electric circuit arrangement for controlling the 40 action of the train stopping mechanism.

Figure 3 is a side elevation of the train stopping apparatus, the cover being removed.

Figure 4 is a top plan view of the same.

45 Figure 5 is a vertical section on the line 5—5 of Figure 4.

Figure 6 is a side elevation of a portion of the same, the cover being shown in section.

50 Figure 7 is a detail horizontal section on the line 7—7 of Figure 5.

Figure 8 is a detail vertical section of the valve operating cam latch structure.

55 Figure 9 is a detail top perspective view of the shoe plate.

Figure 10 is a detail inverted perspective view of the shoe plate.

Figure 11 is a longitudinal section of the resetting air governor valve.

Figure 12 is a longitudinal section of another form of air governor valve for the resetting mechanism.

In the drawings in which like numerals indicate like parts in all of the figures, 1 represents the main reservoir, 2 the equalizing reservoir, 3 the engineer's valve, 4 the train line and 5 the duct from the engineer's valve to the train line, all of which may be of the usual construction.

The apparatus which embodies the present invention includes an air valve mechanism 88 of my approved construction, preferably that disclosed in my co-pending application, filed on even date Serial No. 609,865 which valve mechanism is connected in the line 5 between the engineer's valve 3 and the train line 4, and is operated by an electrically controlled mechanically operated plunger mechanism which forms the subject matter of the present application. The plunger of the valve mechanism is operated by mechanical engagement with a ramp rail 153 located along the right of way and controlled by the track ramp electrical circuit.

The valve operating mechanism.

This mechanism comprises a housing consisting of a base 12, a back wall 13, a removable cover 11, a path clearing plunger device, an operating plunger device, and mechanism operated by the latter for actuating the air valve cam shaft.

The path clearing plunger housing 14 has a bore 15 for the path clearing plunger 16 to whose piston 17 the path clearing shoe 24 is removably fastened. The plunger 16 has a collar 18 fastened to the base 12, the collar having a bearing lining 19 whose squared hole fits the upper squared end of the plunger and prevents its turning.

A cap 20 is fastened in the upper end of the plunger 16 by a retaining screw 21 and lock washer 22.

A spring 23 serves to press the plunger 105 downwardly at all times.

To the lower end of the plunger is fastened, removably, a path clearing shoe comprising a contact plate 25 and a connecting shank 24. The plate 25 is of frusto-conical

form with the end of greatest diameter down and presenting a sharp cutting edge to the ramp. In the upper end of the plate 25 is a circular recess 26 and a counter-bore 31 for the reception of the base 33 of the shank 24 and its locating boss 34. The plate also has a central pocket 32 which is of no special utility in the path clearing shoe, but is useful when the shoe plate 10 is on the operating plunger hereinafter described.

The shank 24 has a duct 36 extending from end to end and communicating at the lower end with the pocket 32 and at the upper end with the duct 45 of the plunger. The operating and path clearing plungers are practically of the same construction for convenience in manufacture.

The plate 25 has a circular groove 28 in the bottom which leaves a central circular core or boss 29 and a web 27, the latter having a series of eight tap holes 30 to receive the two cap screws that pass through the shank base 33 and fasten the plate 25 to the shank.

The boss 29 is of a diameter, in practice, equal to the width of the ramp rail and the eight holes in the plate 25 enable four adjustments of the shoe plate around its axis 30 to be made before it need be discarded because of wear.

35 designates the upper base of the shank which has four screw holes to attach the shank to the lower end of the plunger, the shoe locating recess 37 accommodating a corresponding boss on the lower end of the plunger.

The operating plunger 40 has a piston 41 at the lower end which operates in the bore 39 of the plunger cylinder 38. A spring 40 serves, in cooperation with train line air under pressure, to hold the operating plunger down and to form a progressively increasing resistance against the movement of the operating plunger as it is forced upwardly in passing over the ramp which will insure the greatest contact pressure of the shoe plate 25 against the ramp rail after the shoe plate has ridden up the incline and is in engagement with the top of the ramp rail. This insures good electric contact.

44 is a shoe locating boss on the operating plunger. This plunger is also provided with an air duct 45 extending from end to end, the upper end being counterbored and threaded, at 46, to receive the shank 53 of the plunger head 50 and the gasket 49. The operating plunger has a shoe of the same construction as that of the path clearing plunger and the parts thereof are similarly numbered in the drawings.

The operating plunger 41, like the path clearing plunger, has its upper end flat faced, as at 43, to work in a squared bearing lining 48 in the collar 47, a washer 52 fit-

ting on the squared end 43 of the plunger and being fastened by a cap screw to the lug 51 of the plunger head 50.

A stationary air duct 55 is secured to the back wall 13 and has an inlet port 54 and a piston 56, the latter operating in the piston head cylinder 57 and functions to lead train line air into the plunger head 50 and serves as a piston to compress the air on the up stroke of the plunger head. The plunger head 50 is hollow and its bottom communicates with the plunger bore 45. It also has a cam contacting nose 58 and a reclosing bolt cylinder 59 for the reclosing bolt 60. The bolt 60 has a slot 61 at one side to receive the finger 68 of the bolt projector 62, the latter being operated by the armature carrier 64 and electro magnets 63 when energized.

In order to hold the bolt projector with the bolt projected, while the plunger head is raised, the projector has a stepped heel 66 and a toe 67 between which locking pawl 65 lies, the pawl having a heel 69 by which it is released on contact with the operating plunger collar 47 while the plunger is down and causes the bolt projector to be rocked mechanically back to the position for withdrawing the bolt.

The nose 58 on the up thrust of the plunger engages the valve operating lug 75 of the main cam 74 to turn the main cam in one direction, while the reclosing bolt 60 (when projected) engages the closing lug 76 as the plunger lowers to restore the main cam 74 to its initial position.

77 is the resetting lug of the main cam, which the resetting piston 71 engages to restore the main cam, under the engineer's control, to the initial position.

The resetting piston 71 operates in a cylinder 70 whose inlet 72 communicates with the engineer's resetting valve 8 through ducts 7, 9, 5 etc. The cylinder 70 has outlet ports 73.

The main cam has a locking rib 78 with two notches 79 to hold the cam in either of two positions. The notch 79 which holds the cam to the open position is so designed that when the nose of the plunger head is lowered from engagement with the main cam lug 75 the cam lock will cause a slight backward rotation of the main cam and thus always insure that the air valves are located properly and in a definite position. The main cam also has a stop rib 80 which is adapted to rest against a stop 82 on the journal bracket 81.

The cam lock 84 is pivoted on a support 83 formed on the base of the bracket 81 and carries a roller 85 to engage the locking rib 78 and its notches 79, with which it is held in engagement by a spring 86 on a stud 87 that is threaded into the bracket base and is adjustable to vary the tension of the spring.

The resetting governor allows the engi-

neer to reset the air valve mechanism of the train stopping apparatus only after a predetermined reduction of the train line air pressure has taken place, thus making it impossible for the engineer to nullify a brake action until after a predetermined brake application has occurred.

5 The resetting governor 145 has a port with which the pipe 9 connects and another 10 port with which the pipe 10 connects. It has outlet ports 146 which connect through a pipe 7 with the resetting cylinder 70. A double piston 147-149 is held to close the ports 146 normally by the balanced air 15 pressure at its ends and by the overbalancing spring 151. The position of the pistons due to the spring action is limited by a stop 148 and the distance of movement against the spring tension is such that the piston 147 20 will pass the ports 146 to allow air to escape from pipe 9 to pipe 7 when the pressure in the train pipe connection 10 falls below a predetermined degree (i. e. falls an amount greater than the tension of the spring 151).

25 The electrical connections for controlling the energization of the magnets 63 may be of any approved type, one such being indicated in Figure 2 of the drawings, by reference to which it will be seen that the magnet 30 63 has one terminal connected to the operating plunger 40 and the other terminal grounded to the engine frame.

35 The ramp rail 153 is electrically connected through a signal circuit breaker 154 to the fixed contact points of a track relay 155, the corresponding armature contacts being connected to one terminal of the signal battery 156, the other terminal of which connects with the track rail 157 of one block.

40 The track relay is connected across the track rails of the adjacent block.

158 designates the home signal, one terminal of which connects to one side of the battery 156 while the other terminal connects 45 to the movable relay contact whose opposing stationary contact is connected with the other side of the battery 156.

50 *Operation of the valve operating mechanism.* The drawings show the parts in their respective normal positions.

As the train moves between stations, the shoe 24 of the path clearing plunger 16 removes any snow, ice, frozen mud or other 55 obstruction which might lie in the path of the contact shoe 24 of the operating plunger 40.

When a ramp which is controlled by a "clear" block is reached the first shoe 24 60 glides up the approach slope of the ramp, pushing up the path clearing plunger 16 against the tension of the path clearing plunger spring 23 cleaning the ramp thoroughly by reason of the shoe's scraping corrugations and the heat generated by the

friction caused by the tension of path clearing plunger spring and picking up the electric current from the roadside battery 156.

The reciprocation of the path clearing plunger 16 has no operative effect on the 70 mechanism.

The contact shoe of the operating plunger 40 also glides up the approach slope of the ramp, picking up the current from the roadside battery and pushing up the plunger 75 40 against the tension of operating plunger spring 41 and raising the plunger head 50, which is screwed on the upper end of the operating plunger stem.

The cam contactor 58 of the plunger head 80 50 thereupon engages the valve opening lug 75 of the main cam 74 and oscillates the main cam from its normal position to its abnormal position, a rise of one-half an inch 85 being sufficient to effect this oscillation. The cam lock 84 holds the main cam 74 in this oscillated position against the train vibration. The valve cam (not shown) of the air valve, being rigidly mounted on an extension 90 of the main cam 74 so that it is a part of the same moving unit, thereupon closes the inlet port to the brake pipe by seating the large poppet valve (not shown) of the air valve and opens the outlet port from the 95 brake pipe to the audible signal whistle 6 and the atmosphere by unseating the small poppet valve (not shown) so that the whistle blows while the outlet port is open. For a detailed disclosure of the construction of the poppet valve, etc. attention is directed 100 to my application, Serial No. 609,865 aforesaid.

The current from the roadside battery, which is picked up by both shoes 24 energizes the magnet coils 63 which attract the armature 64 whose upward movement rocks the bolt projector 62 forward and projects the bolt 60. As the bolt projector 62 is rocked forward, the point of the locking pawl 65 105 drops into the step 66 on the lower end of the bolt projector 62 and locks the bolt 60 110 in its projected, or abnormal position.

As the shoe passes down the trailing slope of the ramp, the tension of the operating plunger spring 42 against the operating plunger piston 41 pushes downward the operating plunger 40 and the plunger head 50 attached thereto. The projected bolt 60 thereupon engages the valve closing lug 76 of the main cam 74 and oscillates the main cam reversely to its normal position, where the cam lock 84 again holds it against movement by train vibration.

This reverse oscillation of the main cam 115 74 and the attached valve cam 127 closes the outlet port from the brake pipe to the audible signal whistle and atmosphere and re-opens the inlet port to the brake pipe, re-establishing the manual control of the brakes 120 by the engineer. The outlet port is open 130

such a short interval that there is no appreciable loss of brake pipe air pressure, and yet sufficient air escapes to sound the short blast of the audible signal whistle signifying that the "block" ahead is "clear".

Toward the end of the downward movement of the plunger head 50 the toe of the locking pawl 65 engages the surface of the plunger collar 47 and rises. As its point 10 clears the step of the bolt projector 62, its head engages the extended hub of the bolt projector and forces the bolt projector to retract mechanically the projected bolt 60 so that the parts are again in their 15 respective normal positions as the bottom of the plunger 50 rests against the surface of the plunger collar 47.

When the ramp controlled by a "danger" block is reached, the same mechanical movements take place on the approach slope, except that, as the ramp is de-energized, 20 no roadside current is picked up by the shoes 50, the magnet coils 63 are not energized, the bolt projector 62 is not moved and the bolt 60 not projected. Then when 25 the shoe 24 passes down the trailing slope of the ramp, the valve closing lug 76 is not engaged, the main cam 74 and the attached valve cam (not shown) are not reversely oscillated and the outlet port from the brake pipe to the audible signal and the atmosphere is not closed and the brake pipe air continues to escape. This continued escape 30 of air sounds a long blast on the audible signal whistle and the reduction of brake pipe air pressure starts the triple valves into action and effects a stopping of the train by the normal functioning of air brake apparatus.

An optional feature is the installation of 40 the resetting cylinder 70 and its piston 71. When installed and a de-energizing ramp is passed, an "alive and alert" engineer may 45 manually restore the parts to their respective normal position by operating, with a distinct, specific and unusual act, a resetting valve 8 located in the cab, and introduce a normal brake pipe air pressure in 50 the resetting cylinder 70 behind the resetting piston 71. In being projected by this air pressure, the piston 71 engages the resetting lug 77 on the main cam 74 and reversely oscillates the main cam and the attached valve cam to the respective normal 55 positions. This nullifies the automatic action, and permits the engineer to take manual control of the brakes.

The installation of the governor 145 prevents the engineer nullifying the automatic 60 action, however, until after a predetermined reduction of train line air pressure and the consequent proportionate application of the 65 brakes.

It will be seen with my present arrangement of parts that by controlling the op-

erating plunger as described, the train line air pressure may be utilized in combination with the spring pressure to hold the plunger down in contact with the ramp, the pressure increasing progressively, due to the 70 compression of the spring and to the fact that the piston formed by the stationary air duct 55 serves to compress the air within the plunger bore as the plunger rises, thereby applying corresponding contacting pressure between the shoe plate of the ramp at the time most needed to effect the electrical action. It will also be seen that by the improved construction of the cam lock device I am enabled to assemble the parts 75 thereof as a unit with the main cam journal bracket and provide for an adjustment of the tension of the cam lock on the locking rib of the main cam.

Again it is to be observed that by providing a governor valve in the permissive control air circuit I am enabled to allow the engineer to reset the main cam after an action by the plunger but not until a predetermined application of the brakes has 85 been made through a predetermined reduction of air pressure in the train line. Heretofore permissive control has been regulated by speed governed devices, such for example as that found in my Patent No. 90 1,185,032 issued May 30, 1916, but speed controlled devices have not been found entirely satisfactory owing to the high installation and maintenance costs, all of 95 which objections I avoid by my present arrangement.

In the embodiment of the invention shown in Figure 12 I employ differential pistons, the excess area of the larger over that of the smaller piston determines the overbalancing force normally applied to hold the valve closed. This excess area also determines the reduction of the train line pressure at which the governor valve will move to allow resetting.

While I have shown and described in this application a specific construction of plunger shoe I desire it understood that the same, per se, forms no part of the present invention but constitutes the subject matter 115 of a co-pending application filed on even date herewith, Serial No. 609,865, patent issued July 24, 1923, No. 1,463,105.

While I have shown and described in this application a pressure speed control mechanism for governing the operation of the resetting cylinder and piston, in this application I make no claim thereto, either per se or in combination with the train stopping apparatus as that has been divided out of 125 this application and forms the subject matter of my application filed on the 26th day of April 1923, Serial No. 634,776.

From the foregoing description, taken in connection with the accompanying draw- 130

ings, the complete construction, operation and advantages of the invention will be clear to those skilled in the art.

What I claim is:

5. 1. In apparatus of the class described, a support having a base, a plunger housing projecting from said base, a main cam mounted on the support and having a valve opening lug and a valve closing lug, and a locking rib, a plunger operating in said housing and having a head with provisions for engaging said opening lug on movement of the plunger, and electrically controlled means on said head to engage said valve closing lug, a pivoted cam lock for engaging said locking rib, and a spring for holding said cam lock in engagement.
10. 2. In apparatus of the class described, a support having a base, a plunger housing projecting from said base, a main cam mounted on the support and having a valve opening lug and a valve closing lug, and a locking rib, a plunger operating in said housing and having a head with provisions for engaging said opening lug on movement of the plunger, and electrically controlled means on said head to engage said valve closing lug, a pivoted cam lock for engaging said locking rib, and a spring for holding said cam lock in engagement, and an adjustable spring locating stud for adjusting the tension of said spring.
15. 3. In apparatus of the class described, a support having a base, a plunger housing projecting from said base, a main cam mounted on the support and having a valve opening lug and a valve closing lug, a plunger operating in said housing and having a head with provisions for engaging said opening lug on one movement of the plunger, electrically controlled means on said head to engage the valve closing lug on another movement of said plunger said plunger having a piston and a stem, said plunger housing having a bore to receive said piston and stem, a collar on said base having a bearing through which said stem passes, said stem and collar having provisions to prevent said stem from turning on its axis, said head having a threaded shank to screw into the plunger, a washer on the plunger secured to the head with provisions to engage the plunger and prevent the washer turning on the plunger, to lock the plunger and head together.
20. 4. In apparatus of the class described, a support having a base, a plunger housing projecting from said base, a main cam mounted on the support and having a valve opening lug and a valve closing lug, a plunger operating in said housing and having a head with provisions for engaging said opening lug on one movement of the plunger, electrically controlled means on said head to engage the valve closing lug on another movement of said plunger, said head being hollow and said plunger having an air duct, a fixed air duct in communication with the train line air and telescoping into said head with provisions to effect an air tight joint between said fixed duct and head, thereby to maintain train line air pressure within said head and plunger.
25. 5. In apparatus of the class described, a support having a base, a plunger housing projecting from said base, a main cam mounted on the support and having a valve opening lug and a valve closing lug, a plunger operating in said housing and having a head with provisions for engaging said opening lug on one movement of the plunger, electrically controlled means on said head to engage the valve closing lug on another movement of said plunger, said head being hollow and said plunger having an air duct, a fixed air duct in communication with the train line air and telescoping into said head with provisions to effect an air tight joint between said fixed duct and head, thereby to maintain train line air pressure within said head and plunger, and a spring surrounding said plunger in its housing bore to augment the action of the train line air in forcing the plunger down.
30. 6. In apparatus of the class described wherein is provided an air valve, a cam shaft to open said valve, a plunger to operate said shaft, said plunger and shaft having provisions for releasing the air of the air brake system on removal or breakage of either of said parts; means to apply the air pressure within the plunger to force it down.
35. 7. In apparatus of the class described wherein is provided an air valve, a cam shaft to open said valve, a plunger to operate said shaft, said plunger and shaft having provisions for releasing the air of the air brake system on removal or breakage of either of said parts; means to apply the air pressure within the plunger to force it down, said last named means comprising a stationary element telescoping with air tight connection into said plunger, said plunger having a blind cavity into which said stationary element projects, substantially as shown and described.
40. 8. In apparatus of the class described wherein is provided an air valve, a cam shaft to open said valve, a plunger to operate said shaft, said plunger and shaft having provisions for releasing the air of the air brake system on removal or breakage of either of said parts; means to apply the air pressure within the plunger to force it down, and a spring operating on the plunger to augment the action of the air in forcing the plunger down.
45. 9. In apparatus of the class described wherein is provided an air valve, a cam shaft

to open said valve, a plunger to operate said shaft, said plunger and shaft having provisions for releasing the air of the air brake system on removal or breakage of either of said parts; means to apply the air pressure within the plunger to force it down, said last named means comprising a stationary element telescoping with air tight connection into said plunger, said plunger having a blind cavity into which said stationary element projects, and a spring operating on the plunger to augment the action of the air in forcing the plunger down.

10. In apparatus of the class described, a support including a back wall, a base, and a plunger housing, a plunger operating in said housing, a head on said plunger, a cam shaft operated by said plunger head, said plunger head being hollow and having a cylinder portion, an air duct secured to said back wall and telescoped air tight into said head cylinder portion, means to admit train line air to said air duct, whereby it will enter said head and force said piston downwardly.

11. In apparatus of the class described, a support including a back wall, a base, and a plunger housing, a plunger operating in said housing, a head on said plunger, a cam shaft operated by said plunger head, said plunger head being hollow and having a cylinder portion, an air duct secured to said back wall and telescoped air tight into said head cylinder portion, means to admit train line air to said air duct, whereby it will enter said head and force said piston downwardly, said plunger having a piston and a stem within said plunger housing and a spring within the housing surrounding the stem and engaging the plunger piston to operate in conjunction with the air pressure in forcing the piston downwardly.

12. In an apparatus of the class described, a support, a plunger housing thereon, a plunger operating in said housing, a main valve operating cam carried by said support to operate with said plunger, said plunger including a head having a cylinder portion, said plunger having a longitudinal bore communicating with the interior of said cylinder portion at one end and being blind

at the other end, a fixed piston member mounted on the support to enter said cylinder portion, a spring surrounding the plunger within said plunger housing to augment the action of the air pressure within said cylinder portion to force said plunger down, and means for admitting train line air into said cylinder portion through said fixed piston for the purposes specified.

13. In apparatus of the class described, a main valve operating cam, a plunger with a head to operate said cam in one direction and an electro magnetically projected bolt on said head to operate said cam in the other direction, a bolt projector comprising a pivoted body with a finger engaging said bolt and itself engaged by the armature of an electro magnet, said bolt projector having a locking step and a toe, a locking pawl engaging the step and toe, the engagement being such that said pawl will retract said bolt projector on the down stroke of the plunger, and said bolt projector will overcome the inertia of said pawl when the plunger is elevated and the magnet energized, and a fixed element against which said pawl engages as the plunger arrives approximately at the lower limit of its stroke.

14. In mechanical valve operating mechanisms for train stopping systems wherein is provided an air valve, a cam shaft to open said valve, a plunger to operate said cam shaft, said cam shaft and plunger having provisions for releasing the air of the air brake system on removal or breakage of either of said parts; said plunger comprising a piston and a stem, a shoe on the lower end of the piston, an operating head on the upper end of the stem, said head, said stem and said shoe having an air duct terminating in the shoe, said head having a cylinder, a fixed air duct telescoped through said head for delivering the air into said head, and means for leading train line air to said fixed air duct, at all times, said fixed air duct having a piston of greater diameter than the passage through the air duct, and a spring for assisting the air pressure in the air duct to force the plunger downwardly.

JEAN FRANCIS WEBB, JR.
